CLAIM

The ornamental design for a foldable bedside sleeper, as shown and described.

DESCRIPTION

FIG. 1 is a top and front perspective view showing of a foldable bedside sleeper showing my new design;
 FIG. 2 is a rear and bottom perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof;
 FIG. 8 is a bottom plan view thereof; and,
 FIG. 9 is another perspective view showing the foldable bedside sleeper in folded state.
 The broken lines in the figures illustrate portions of the foldable bedside sleeper that form no part of the claimed design.
